UNITED STATES PATENT OFFICE.

CHARLES A. WILLMARTH, OF DETROIT, MICHIGAN, ASSIGNOR TO MAJESTIC WIRE FENCE CO., LTD., OF DETROIT, MICHIGAN.

FENCE-POST.

SPECIFICATION forming part of Letters Patent No. 759,838, dated May 10, 1904.

Application filed August 17, 1903. Serial No. 169,682. (No model.)

To all whom it may concern:

Be it known that I, CHARLES A. WILLMARTH, a citizen of the United States of America, residing at Detroit, in the county of Wayne and State of Michigan, have invented certain new and useful Improvements in Fence-Posts, of which the following is a specification, reference being had therein to the accompanying drawings.

10 This invention relates to improvements in metallic fence-posts; and its object is to provide a very light post having great strength and to form the same by stamping, with simple and efficient means for detachably securing the fence-wires thereto.

15 It is also an object of the invention to provide a post having certain other new and useful features, all as hereinafter more fully described, reference being had to the accompanying drawings, in which—

20 Figure 1 is a perspective view of a post embodying the invention; Fig. 2, a similar view on a smaller scale and showing the post provided with an anchor-plate and the rod for securing the wires in place detached. Fig. 3 is a detail showing a transverse section through one of the notches, and Fig. 4 a detail showing the manner in which the anchor-plate is attached.

25 30 A is the body of the post formed of angle-iron and in cross-section is preferably in the form of a Y, the flanges *a b* being equal in width and extending at right angles to each other and the flange *c* being of slightly-greater width than the others and extending from the point of the angle formed by the meeting of the other flanges.

35 B represents notches formed in the edge of the flange *c* by stamping, and the metal thus severed is turned outward at right angles to form ears C, a hole being stamped in each of said ears at the same time that the ear is stamped out to receive the rod D. The notches are spaced according to the desired spacing of the line-wires of the fence or a greater number may be made, so that the fence may be spaced as desired upon the post, and in building the fence the line-wires are strung through the notches and then the rods slipped

through the openings in the ears to lock the wires in the notches. The upper end of the rod is bent to hold it from slipping through, and all of the ears except the one nearest the top of the post are formed so that they are integral with the flange at the bottom of the notch and the wires are supported by the ears; but the upper ear is formed integral with the flange at the top of the notch, so that the rod will extend across the same and hold the wire therein. The rod may also be bent at its lower end to prevent its being accidentally withdrawn.

40 The ordinary line-posts are left straight at their lower ends, as shown in Fig. 1, and may be driven into the ground to the proper depth; but where the strain of the fence has a tendency to lift the posts out of the ground, as in the hollows between knolls, the flanges are split apart upward a short distance from the lower end of the post and bent outward to form lugs 45 E', to which the anchor-plates E, consisting of a rectangular metal plate or plank, is secured by bolts. These anchor-plates prevent the posts from being lifted out of the ground by the fence, and thus a very strong and practically indestructible fence is provided which may be easily moved, if desired, or the fence quickly and easily attached to or detached from the posts without injury to either.

45 50 Other forms of angle-iron may be used; but I prefer the Y form, as the flanges extending from a common center stiffen the body against strains in any direction and the flange *c*, being wider and extending in the direction it does from the other flanges, offers 55 the best facility for forming the notches and attaching the wires.

55 60 The body of the post being formed of material which may be obtained in the market and the means for fastening the wires formed 65 by stamping up the metal of the body, a very cheap construction is obtained and strong and efficient fastening means secured.

Having thus fully described my invention, what I claim is—

65 70 75 1. In a fence-post, the combination of a body portion having a flange provided with notches to receive the line-wires of the fence,

said notches being formed by cutting inward and downward from the edge of the flange, ears provided with openings formed on said flange by bending the metal severed in forming the notches outward at right angles from the bottom of said notches and means engaging the openings in the ears to secure the wires in the notches.

2. In a fence-post, the combination of a body portion formed of Y-shaped angle-iron, one flange of which is wider than the other two, ears and notches formed at the edge of the wider flange by stamping the metal up each ear being provided with an opening, a rod to engage the openings in the ears and having a laterally-bent upper end, lugs formed on the lower end of the body by bending its

flanges outward, and an anchor-plate secured to said lugs.

3. In a fence-post, the combination of a body portion formed of Y-shaped angle-iron, notches formed in the edge of one of said flanges by punching out the metal to form laterally-projecting ears having openings, the upper one of said ears being formed integral with the upper side of its notch and the lower one integral with the lower side of its notch and a rod to engage the openings in said ears.

In testimony whereof I affix my signature in presence of two witnesses.

CHARLES A. WILLMARTH.
